UNITED STATES PATENT OFFICE.

ERNEST SCHWARZ, OF LANCASTER, PENNSYLVANIA.

DESIGN FOR A HANDLE FOR CARVING SETS.

43,381.

Specification for Design.

Patented Dec. 24, 1912.

Application filed August 20, 1912. Serial No. 716,107. Term of patent 3½ years.

To all whom it may concern:

Be it known that I, ERNEST SCHWARZ, a citizen of the United States, residing at Lancaster, in the county of Lancaster and State of Pennsylvania, have invented a new, original, and ornamental Design for a Handle for Carving Sets, of which the following is a specification, reference being had to the accompanying drawing, forming part thereof.

Figures 1 and 2 show the two sides of the handle.

I claim:

The ornamental design for a handle for carving sets, as shown.

ERNEST SCHWARZ.

Witnesses:

JOHN J. THOMPSON,
W.M. J. COULTER.
